UNITED STATES PATENT OFFICE.

CARL A. HUBER, OF ROCHESTER, NEW YORK.

RAILROAD-CROSSING.

1,242,696.

Specification of Letters Patent.

Patented Oct. 9, 1917.

Application filed August 9, 1916. Serial No. 113,898.

To all whom it may concern:

Be it known that I, CARL A. HUBER, of Rochester, in the county of Monroe and State of New York, have invented certain new and useful Improvements in Railroad-Crossings; and I do hereby declare the following to be a full, clear, and exact description of the same, reference being had to the accompanying drawings, forming a part of this specification, and to the reference characters marked thereon.

My invention has for its purpose to afford a safe-guard for railroad crossings of the type where the highway is upon the same level with the tracks or rails, and to accomplish this object by compelling one driving along the highway to retard the rate of travel to a moderate speed before crossing the tracks, and to drive for a short distance in the same general direction as the tracks and within plain sight of them, so that the vehicle may be under perfect control during the act of crossing and the driver may have a reasonable chance of learning of the approach of a train before crossing. To these and other ends the invention consists in certain improvements in railroad crossings, all as will be hereinafter more fully described, the novel features being pointed out in the claims at the end of the specification.

In the drawings:

Figure 1 is a plan view showing a railroad crossing constructed in accordance with my improvement, and

Fig. 2 is a plan view of a modified form in which the main road or highway approaches the railroad tracks at an angle other than ninety degrees.

My invention is designed to solve the problem presented by the numerous accidents and fatalities due chiefly to the increasing use of motor vehicles and the carelessness or forgetfulness displayed by drivers when crossing railroad tracks. A viaduct or bridge, is of course a safe solution, but to install these at every rural railroad crossing throughout the extensive railroad systems would involve an expense that makes it prohibitive and it is my purpose to construct a grade crossing at a comparatively nominal cost and provide an arrangement that will effectually prevent a driver from crossing a railroad track at any other than an extremely moderate rate of speed and without making at least a casual

observation before crossing, to determine if there is an approaching train.

With this brief general outline the invention consists more particularly in providing an offset portion in the main road or highway which will necessitate the driver's making a sharp turn from the path of the main highway before crossing the railroad track, the offset portion including a crossing road extending over the track. The crossing road is preferably connected with the main highway, on both sides of the track, with stretches of road that extend generally in a direction at an angle to the main highway and these connecting stretches between the main road and the crossing road are preferably parallel to the track. They extend for a distance sufficiently close to and in the general direction of the railroad track to afford an opportunity for a driver of a vehicle traveling on them to observe the railroad track in either direction before crossing it, thus giving him a fair opportunity to discover the approach of a train. While it may be said that under ordinary present conditions of a grade crossing, a driver is enabled to observe the approach of a train from either direction, the safety feature is absent because in the majority of cases the speed of the vehicle is not sufficiently decreased when nearing a railroad track to afford a driver the proper opportunity for observation, whereas with my present construction the turns in the road from the main highway into the stretches leading to the crossing road and from the stretches into the crossing road, necessitate decreasing the speed so materially as to preclude the probability of not hearing or seeing an approaching train. It is possible to insure turning from the main road into the lateral stretches by providing obstructions in the path of the main highway between it and the railroad track so that of necessity a vehicle driver must turn from the main road and approach the crossing road by traveling in the same general direction as the track and in full view of it, and is effectively prevented from driving directly across the track in the general direction of the highway.

I have disclosed in this application two general adaptations of my invention which are illustrative of practicable methods of carrying it out, although other modifica-

tions may be adopted without departing from the underlying features and spirit of the invention. In Fig. 1 there is represented a main road or highway approaching the railroad at right angles and designated by A, while B are the tracks of the railroad. C designates the crossing road extending over the tracks B and offset from the main road A. The crossing road C is connected 10 with the main road A by stretches D which extend along the railroad tracks and sufficiently close to keep them in full view and in a direction at an angle to the main road A and preferably parallel to the tracks B 15 although the purpose may be accomplished by having the stretches D in other than a parallel relation to the tracks as long as they serve to offset the crossing road from the main road and necessitate a double turn 20 from the main road before reaching the railroad tracks, and also cause a vehicle driver to proceed in the general direction of the tracks for a short distance and in full view of them. While I do not intend to limit 25 the length of the road stretches D, it is to be understood that they need not be unnecessarily long but only of sufficient extent to cause the driver to proceed in view of the tracks at slow speed far enough to permit 30 him having reasonable warning of an approaching train and for ordinary purposes it would be sufficient if the road stretches D are of the same length or slightly longer than the length of the crossing road C. In 35 order to insure making the turn from the main road into the stretches D, and effectually obviate crossing the tracks in the direct line of the main highway I may provide obstacles or abutments E of any suitable 40 form and arrange them in the path of the main road and between it and the railroad tracks as shown in Fig. 1.

Fig. 2 illustrates a modification of the idea for application to a road approaching a railroad track at an angle other than a right angle, and in this form, the main road is designated at F and the crossing road at G while the latter is connected with the main road on opposite sides of the track 45 by the stretches H extending in the same general direction as the railroad track and preferably parallel thereto. In the particular arrangement shown, the road stretches H are of unequal length although they may 50 be made of the same length or the crossing road G may extend across the tracks at an angle other than a right angle without departing from the underlying feature of my improvement which consists in providing 55 a crossing road extending over a railroad track or tracks and offset from the main road or highway, the crossing road being reached from the main road by stretches extending in full view of the railroad 60 and in the same general direction.

Applicant's structure consists in a highway road with an offset portion which at its outer part crosses a railroad track at a distance from the main line of the highway and includes lateral road stretches extending for track observation purposes along or in the general direction of the track and connecting the track crossing portion of the highway with its main line, and wherein the double turns of the highway at the junction of its main line with the lateral road stretches and at the junction of said stretches with the track crossing portion of the highway, are formed in sufficiently sharp curves or bends to compel an ordinary vehicle 70 rapidly traveling on the highway to slacken its speed as it approaches the railroad track from either direction and thus assure its safe crossing of the railroad track.

It is common in cities or towns to lay out 85 intersecting streets with rounded park or monument sites interposed at their junction and to extend flush-laid railroad tracks along one of the streets and clear across the rounded open area at said junction, but this 90 relative arrangement of streets and railroad tracks does not provide sufficiently abrupt turns or bends of the street which crosses the tracks to positively compel slackening of the speed of an automobile or other ordinary vehicle rapidly passing through the street, prior to crossing the tracks, and therefore, the obviously valuable life-saving benefits and advantages of this invention 95 are not here realized. These benefits and 100 advantages can be realized only by such relative arrangement of the highway and the railway tracks as will compel slackening of the speed of an ordinary vehicle rapidly 105 traveling on the highway, before crossing the tracks, while also giving ample opportunity while traveling over the comparatively long lateral stretches of the offset portion of the highway, to discover the presence of a train or car approaching the 110 highway on the tracks from either direction, to promote or assure the safety of passengers in a vehicle about to cross the railway tracks.

I claim as my invention:

1. In railroad crossings, the combination 115 with a railroad track, of a highway road approaching the track from one side and continuing at its opposite side and having an intermediate offset portion crossing the 120 railroad track at a place distant from the main line of the highway, said track crossing highway portion being connected to the main line of the highway by lateral stretches 125 thereof extending one at each side of the railroad track and in the same general direction and giving full view of the track from a vehicle traveling on said lateral stretches in either direction, said lateral highway 130 stretches being connected to the main line

- of the highway and to the railroad crossing portion thereof by sharp curves or bends compelling an ordinary vehicle rapidly moving on the highway to slacken its speed
- 5 as it approaches and crosses the railroad track from either direction, said lateral highway stretches also having a length equal to or greater than the length of the track crossing portion of the highway.
- 10 2. In railroad crossings, the combination with a railroad track, of a highway road approaching the track from one side and continuing at its opposite side and having an intermediate offset portion crossing the
- 15 railroad track at a place distant from the main line of the highway, said track crossing highway portion being connected to the main line of the highway by lateral stretches thereof extending one at each side of the railroad track and in the same general direction and giving full view of the track from a vehicle traveling on said lateral stretches in either direction, said lateral highway stretches being connected to the main line
- 20 of the highway and to the railroad track crossing portion thereof by sharp curves or bends compelling an ordinary vehicle rapidly traveling on the highway to slacken its speed as it approaches and crosses the railroad track from either direction, and obstructions located in the line of the highway where it merges into its offset portion and assuring passage from the highway into its offset portion of an ordinary vehicle approaching said offset highway portion from either side of the railroad track.
- 25 3. In railroad crossings, the combination with a railroad track normally obstructing the crossing of ordinary vehicles, of a highway road approaching the railroad track from one side and continuing at its opposite
- side and having an intermediate communicating offset portion crossing the railroad track and built up about level therewith to insure safe passage of ordinary vehicles 45 across the track at a place distant from the main line of the highway, said offset highway portion including lateral stretches thereof ranging one at each side of the railroad track and in the same general direction 50 and giving full view of it from a vehicle traveling on the highway in either direction.
4. In railroad crossings, the combination with a railroad track normally obstructing the crossing of ordinary vehicles, of a highway road approaching the railroad track from one side and continuing at its opposite side and having an intermediate communicating offset portion crossing the railroad 55 track and built up about level therewith to insure safe passage of ordinary vehicles across the track at a place distant from the main line of the highway, said offset highway portion including lateral stretches 60 thereof ranging one at each side of the railroad track and in the same general direction and giving full view of the track from a vehicle traveling on said lateral stretches in either direction, said lateral highway stretches being connected to the main line of the highway and to the railroad track crossing portion thereof by sharp curves or bends compelling an ordinary vehicle rapidly traveling on the highway to slacken its speed as it approaches and crosses the railroad track from either direction. 70
